GAS COCK

William S. Kincaid, Detroit, Mich., assignor to
The Roberts Brass Manufacturing Company,
Detroit, Mich., a corporation of Michigan

Application September 25, 1944, Serial No. 555,683

9 Claims.

(CL 277—66)

1

The invention relates to gas cocks more particularly designed for use in controlling gas burners.

It is the object of the invention to obtain a construction by which the cock may be adjusted to a plurality of different positions for imposing different restrictions to the flow of gas so as to correspondingly regulate the flame of the burner. To this end the invention consists in the construction as hereinafter set forth.

In the drawings:

Fig. 1 is a side elevation of my improved gas cock;

Fig. 2 is an elevation viewed at right angles to Fig. 1 and with the cap and valve plate removed;

Fig. 3 is an elevation of the valve plate;

Fig. 4 is a cross section on line 4—4, Fig. 1;

Fig. 5 is a cross section on line 5—5, Fig. 1;

Fig. 6 is a similar section with the latch member removed;

Fig. 7 is a plan view of the latch plate detached;

Fig. 7A is a side elevation thereof;

Fig. 8 is an enlarged section through the cock on line 8—8, Fig. 1;

Figs. 9, 10 and 11 are views similar to Fig. 8 showing the plug valve in different positions of adjustment;

Fig. 12 is a view similar to Fig. 2 showing the valve plate in position but with the cap removed; and

Fig. 13 is an elevation of the plug valve and latch plate removed from the casing.

The cock is of the type comprising a casing A having a tapering rotary hollow plug valve B therein provided with a port C for registering with the inlet passage D in the casing. The outlet passage E is in alignment with the plug and is in constant communication with the chamber therein. Thus, when the plug valve is turned with the port C out of registration with the passage D, communication between the passages D and E is cut off. On the other hand, when the port C is in full or partial registration with the passage D, gas will flow from the latter to the outlet E.

The construction as thus far described is the ordinary construction of gas cock. With this it is possible to regulate the flow of gas therethrough by turning the plug into different positions but it is difficult to accomplish this with any desired degree of accuracy. It is, therefore, the primary object of my invention to obtain a construction in which different positions of adjustment of the valve will predeterminedly control the flow of the

2

gas therethrough with great accuracy. This is accomplished by the following construction. Within the casing A at one side thereof is formed a chamber F which is connected to the inlet passage D by a bypass G. The chamber F is also connected with a plurality of ports H, I leading to the seat for the plug valve B. These ports are so positioned that the port C of the valve may be registered with each when completely out of registration with any other port or with the passage D. Thus, the flow of gas will be through the bypass to the chamber F and from the latter through the port in registration with the port C to the chamber within the valve and thence to the outlet E. By variably restricting the ports H and I, the gas will flow therethrough at different rates to correspondingly regulate the burner flame.

To permit of variably restricting the ports H and I, I have provided screw-threaded metering pins J and J'. These engage correspondingly threaded apertures in a closure plate K for one side of the recess F which plate engages a shoulder in a nipple A' on the casing A. The plate is secured to the casing by screws L and the metering pins J and J' extend respectively into the ports H and I and may be adjusted to variably restrict the same. Slotted heads J² on these pins are engageable for adjustment by a screwdriver, and springs J³ between said heads and the plate K hold the same in adjusted position. The plate K and pins J and J' are enclosed by a cap M threadedly engaging the nipple A'.

The valve B has an operating stem N extending outward therefrom being flattened on one side for non-rotatably engaging a socket in the handle member O. To hold the valve in its different positions of adjustment, I have provided a latch mechanism comprising a member P slidably and non-rotatably engaging the flattened stem N. A spring Q on the stem yieldably urges the member P in an outward direction. R is a plate secured to the casing A by screws R' and apertured for the passage of the stem N. This plate has a plurality of rounded projections R² for engagement with recesses P' in the member P. These projections and recesses are so located as to engage with each other in the different positions of adjustment of the valve in which the port C is registered respectively with the passage D, the port H or the port I. The spring Q yieldably presses the member P against the plate R so that the projections R² will snap into latching engagement with the recesses P' in each position of adjustment but without interfering with fur-

ther adjustment when desired. A projection P^2 on the member P engages shoulders A^2 on the casing A to limit the rotative adjustment of the stem. Thus, in use the operator by turning the handle O can adjust the cock from the position shown in Fig. 9 where the gas is completely cut off to any one of the positions respectively shown in Figs. 8, 10 and 11. In Fig. 8 the flow of gas from the inlet D to the outlet E is unrestricted. In Fig. 10 the flow through the port I is restricted by the metering pin J' and in Fig. 11 the flow through the port H is restricted by the metering pin J .

To adjust the valve for use with different line gas pressures, the cap M may be removed and the metering pins J and J' adjusted by a screwdriver until the desired flow of gas is obtained through each of the ports H and I . The cap M may then be replaced. In the process of construction, the chamber F is formed in the nipple A' before the ports H and I and by-pass G are formed in the casing A . By referring to Figs. 8, 9, 10 and 11 respectively, it will be noted that the chamber F is at the outer ends of the ports H and I and by-pass G , hence said ports H and I and by-pass G may be formed by drilling the casing A from the base of the chamber F before the closure plate K and cap M are applied to said casing. Gas is always free to flow from the inlet passage D via the by-pass G to the chamber F , and the metering pins J and J' carried by said closure plate K control the flow of gas from said chamber F to the port C in the valve B .

What I claim as my invention is:

1. A valve cock comprising a casing having a seat for a rotary valve, inlet and outlet passages leading from said seat, said outlet passage being in axial alignment with said seat, and said inlet passage extending laterally from said seat, a chamber at one side of said seat and opening outwardly, a by-pass between said inlet passage and said chamber, a pair of laterally spaced ports extending between said chamber and valve seat, the construction and arrangement of said by-pass, spaced ports and chamber being such that said spaced ports and by-pass are accessible from said chamber and may be formed in said casing by drilling said casing from the base of said chamber, a removable closure for said chamber, means carried by said closure for controlling said spaced ports, and a rotary valve engaging said seat and having a port adapted to register with said inlet passage and alternately with said spaced ports.

2. In a valve of the class described, a valve body having a chamber for a rotary valve, inlet and outlet passages communicating with said chamber, said valve body having an outwardly open recess at one side of said chamber, a by-pass from said inlet passage to said recess, a plurality of spaced passages connecting said recess with said chamber, a removable closure plate for said recess, detachable means accessible from the exterior of said body for securing said plate over said recess, individually adjustable metering means carried by said plate for controlling said spaced passages, and a rotary valve in said chamber having a port adapted to register with said inlet passage and alternately with said spaced passages.

3. In a valve of the class described, a valve body having a chamber for a rotary valve, inlet and outlet passages communicating with said chamber, said valve body having an outwardly open recess at one side of said chamber, a by-pass from said inlet passage to said recess, a plurality

of spaced passages connecting said recess with said chamber, a removable closure plate for said recess, detachable means accessible from the exterior of said body for securing said plate over said recess, separately adjustable metering means carried by said plate for controlling said spaced passages, a removable cover plate concealing and protecting said closure plate and said metering means, and a rotary valve in said chamber having a port adapted to register with said inlet passage and alternately with said spaced passages.

4. In a valve of the character described, a valve body having a valve chamber for the reception of a rotary valve, an inlet passage and a plurality of ports spaced circumferentially around said chamber, an outlet passage leading from said chamber, an outwardly open recess in said body at the outer ends of said spaced ports, a by-pass between said inlet passage and said recess, a removable closure plate for said recess, separately adjustable metering means carried by said plate for controlling said spaced passages, and a rotary valve in said chamber having a port adapted to register with said inlet passage and alternately with said spaced ports.

5. In a valve of the character described, a valve body having a valve chamber for the reception of a rotary valve, an inlet passage and a plurality of ports spaced circumferentially around said chamber, an outlet passage leading from said chamber, an outwardly open recess in said body at the outer ends of said spaced ports, a by-pass between said inlet passage and said recess, a removable closure plate for said recess, means carried by said plate for controlling said spaced passages, and a rotary valve in said chamber having a port adapted to register with said inlet passage and alternately with said spaced ports.

6. A gas cock comprising a casing having a seat for a rotary valve, inlet and outlet passages leading from said seat, a chamber at one side of said seat and opening outwardly, a by-pass between said inlet passage and said chamber, a plurality of ports leading from said chamber to spaced points of said valve seat, a removable closure plate for said chamber, separately adjustable metering pins threadedly engaging said closure plate respectively in alignment with said spaced ports and accessible externally of said chamber for adjustment purposes, and a rotary valve engaging the seat aforesaid and having a port adapted to register with said inlet passage and alternately with said spaced ports.

7. A gas cock comprising a casing having a seat for a rotary valve, inlet and outlet passages leading from said seat, a chamber at one side of said seat and opening outwardly, a by-pass between said inlet passage and said chamber, a pair of substantially parallel ports leading from said chamber to spaced points of said valve seat, substantially parallel separately adjustable metering pins for controlling said parallel ports, a common carrier for said metering pins carried by said casing and forming a closure plate for the chamber aforesaid, said closure plate being removable from said casing, and a rotary valve engaging the seat aforesaid and having a port adapted to register with said inlet passage and alternately with said spaced ports.

8. A gas cock comprising a casing having a seat for a rotary valve, inlet and outlet passages, the outlet passage being in axial alignment with said seat and the inlet passage extending laterally from said seat, a chamber at one side of said seat and opening outwardly, a by-pass between

said inlet passage and said chamber, a plurality of ports leading from said chamber to spaced positions in said valve seat, a removable closure plate for said chamber, separately adjustable metering pins threadedly engaging said closure plate respectively in alignment with said ports and adjustable externally of said chamber, a cap for enclosing said metering pins, and a rotary valve engaging said seat and having a port adapted to register with said inlet passage and alternately with said spaced ports, the construction and arrangement of said chamber, spaced ports and by-pass being such that said spaced ports and by-pass may be formed in said casing by drilling the latter from the base of said chamber before the closure plate and cap are applied to said casing.

9. A gas cock comprising a casing having a seat for a rotary valve, inlet and outlet passages, the outlet passage extending axially of said seat and the inlet passage extending laterally from said seat, a laterally extending chambered nipple with the chamber thereof opening outwardly, a by-pass between said inlet passage and said chamber, a plurality of ports leading from said chamber to spaced positions in said valve seat, a removable closure plate for the chamber in said nipple, separately adjustable metering pins

5
10

threadedly engaging apertures through said plate and in alignment respectively with said ports, said pins being externally adjustable to variably restrict said ports, a cap threadedly engaging said nipple to enclose said metering pins, a rotary valve engaging said seat in constant communication with said axial passage and having a port adapted to register with said inlet passage and alternately with said spaced ports, and a latch mechanism for yieldably holding said valve in different positions where the port therein is in registration respectively with said inlet passage and said spaced ports.
